UNITED STATES PATENT OFFICE.

FRANK GASPAR, OF CUPAR, SASKATCHEWAN, CANADA.

CABLE AND TELEPHONE-WIRE CONTAINING RAIL.

1,401,531.

Specification of Letters Patent. Patented Dec. 27, 1921.

Application filed September 1, 1921. Serial No. 497,547.

To all whom it may concern:

Be it known that I, FRANK GASPAR, citizen of Canada, residing at Cupar, in the District of Humboldt and Province of Saskatchewan, Canada, have invented certain new and useful Improvements in Cable and Telephone-Wire Containing Rails, of which the following is a specification.

This invention relates to a railroad telephone system whereby telephoning may be done from moving trains and it has for an object to provide a simple system for this purpose which may also be used by station agents along the railroad.

For further comprehension of the invention, and of the objects and advantages thereof, reference will be had to the following description and accompanying drawings, and to the appended claims in which the various novel features of the invention are more particularly set forth.

Figure 1 of the drawings is a transverse sectional view showing a track rail and its support with the invention applied thereto.

Fig. 2 is a similar view but taken at a different point.

Fig. 3 is a transverse sectional view illustrating the manner of connecting the stations along the line to the system.

Fig. 4 is a plan view of a portion of a railroad track having the invention applied thereto.

Fig. 5 is a side elevation of a portion of the track, indicating part of a railroad train in position thereon.

In the drawings the reference numeral 10 indicates a pair of track rails, and 11 the ties on which the rails rest. Each of these rails has a thickened web formed partly by an integral member 10' and partly by a supplementary member 12 having a dove-tail tongue and groove connection 13 with the member 10'.

The web member 10' presents a longitudinal recess on its inner face which recess is closed on its fourth side by the tongue of member 12. This recess serves as a conduit for a series of wires, indicated at 15.

These wires 15 are connected to different sections of a contact rail 17 set in, and extending along, an insulating base element 18 on the rail, this insulating base element being here shown as connected to the rail by a tongue and groove connection 19, while the rail has a tongue and groove connection 17' with the element 18.

To effect the electrical connections between the wires 15 and the various sections of contact rail 17, the ends of the wires are fastened by screws such as 20 to blocks 21 located under the recesses in the rail members 10'. The underside of each block is engaged by a stud 22 having a cupped enlargement 23 on its lower end engaged in a suitable recess in the tie 11, the studs 22 being pressed upward against the blocks 21 by a coiled expansion spring 24. A similar stud 30, having a cupped enlargement 31 on its lower end is pressed by a spring 32 against the underside of each section of the contact rails 17. Contact is maintained between the members 23 and 31 by means of a bar 33 having semi-circular ends 34 which engage the sides of said members. To secure these parts in place suitable recesses are formed in the bottom of the ties 11 and are closed by filler blocks 35 held in place by screws 36. These filler blocks serve as abutments for the springs 24 and 32. The wires 15, blocks 21, screws 20 and studs 22 are insulated from the rail 10 by insulating lining indicated at 37.

These rails are adapted to be engaged by wheels 40 on the lower ends of spring pressed trolley poles 41, of ordinary construction through which passes lead wires to telephones, indicated at 43, which may be placed in various parts of the train as desired, being shown in the engine 44 and one of the coaches 45 in Fig. 5.

As here shown, each of the track rails is equipped with the devices above described to permit of two people telephoning from the train at the same time. The return connection is effected by grounding one side of the train telephones and main office telephones.

The wires 15 as above set forth, are connected at one end to the respective contact rail sections 17, it being understood that these wires connect at opposite ends to any suitable type of switchboard or telephone apparatus in a well known manner, which is preferably located in the train dispatcher's office. Since each contact rail section has an individual connection with the switchboard it follows that individual communication can be had by trains on different sections with the operators in the office where the switchboard is located.

As shown in Fig. 3 I provide a connection to permit of station agents along the rail-

road using the system to telephone to the main office. As there shown the cupped end 31 of the stud 30 engaging the adjacent contact rail section has a tube 50 connected thereto into which the end of the station telephone wire 51 is led and to which it is fastened, this tube being accommodated in a slot 52 in the tie 11.

Having thus described my invention what 10 I claim as new and desire to protect by Letters Patent of the United States is as follows:

1. A track rail having a thickened web formed with a longitudinal recess, a supplementary web element covering said recess, a contact rail supported adjacent to and insulated from the track rail and divided into sections, wires in said recess, said wires being individually connected to the respective sections of the contact rail.

2. A track rail having a thickened web formed with a longitudinal recess, a supplementary web element covering said recess, a contact rail supported adjacent to and insulated from the track rail and divided into sections, wires in said recess, said wires being individually connected to the respective sections of the contact rail, the connections between said wires and rail sections comprising blocks to which the ends of the wires are secured, and spring pressed studs engaging said blocks.

3. A track rail having a thickened web formed with a longitudinal recess, a supplementary web element covering said recess, a sectional contact rail supported adjacent to and insulated from the track rail, wires in said recess, blocks to which said wires are connected at one end, studs adapted to bear upwardly against said blocks and rail sections, cupped enlargements on the lower ends of said studs, springs bearing upwardly in said cupped enlargements, and electrical connection devices between the respective cupped enlargements. 45

4. A track rail having a thickened web formed with a longitudinal recess, a supplementary web element covering said recess, a sectional contact rail supported adjacent to and insulated from the track rail, wires 50 in said recess, blocks to which said wires are connected at one end, studs adapted to bear upwardly against said blocks and rail sections, cupped enlargements on the lower ends of said studs, springs bearing upwardly in said cupped enlargements, and electrical connection devices between the respective cupped enlargements, said devices comprising bars having semi-circular ends fitting against the said cupped enlargements. 55 60

In testimony whereof I have affixed my signature this 16th day of August, 1921.

FRANK GASPAR.
